UNITED STATES PATENT OFFICE

2,605,073

MAILBOX SUPPORT

Glenn Buck, Wittenberg, Wis.

Application August 5, 1948, Serial No. 42,629

2 Claims. (Cl. 248—204)

1

My invention relates to improvements in mailbox support and more particularly to supports arranged for suspending rural mail boxes.

The object of my invention is to provide a support for mail boxes that will permit the box to be extended outward from a mounting to facilitate the approach thereof.

Another object of my invention is to construct a device of the character described in a manner that will retain the mail box in a horizontal position by means of gravity due to the angular method of mounting.

Still another object of my invention is to provide a support that will yield in either direction when contacted by an impact.

A still further object of my invention is to provide a support that will retain the mail box in proper alignment by means of a resilient spring member.

It is manifest to anyone familiar with the mounting of rural mail boxes, that it is imperative to support the mail box outward from its point of attachment so that the postal employee making the deliveries which is usually done from a vehicle, has ready access to the box without having to get too far off the road in bad weather or the like. It is also obvious that a mail box suspended in this manner is in danger of receiving an impact from a snow plow or the like and must be mounted in a manner to permit it to yield in either direction with the impact, and retain its original position after the impact. All of these features are incorporated in the device described and claimed herein.

Other and further objects of my invention will become more apparent as the description proceeds when taken in conjunction with the drawings in which

Figure 1 is a perspective view of the assembled device supported from a mounting shown as a vertical post.

Figure 2 is a bottom view of the mail box and guard arrangement when mounted to a horizontal rod.

Figure 3 is a fragmentary cross sectional view of the mounting post and bracket arrangement.

Figure 4 is a detailed fragmentary view of the end of the spring leaf in its contact with the rod and

Figure 5 is a cross sectional view of the contact arrangement taken at the line 5—5 in Figure 4.

Similar characters of reference indicate corresponding parts throughout the several views, and referring now to the same, the character 10 shows a conventional type of mail box such as is usually

found in rural districts. The box 10 is shown suspended outward on the top of a horizontal rod shown as 11 which forms a part of the entire mounting when used in conjunction with an angularly disposed rod 12, which is shown fastened to the horizontal rod 11 by means of a coupling 13 or in any other convenient manner. Obviously, the rods 11 and 12 may be integrally formed if desired so that they will be constructed of a single piece.

There is a bracket 14 which is constructed of flat steel or the like, having an outwardly projecting upper end 15 and a lower outwardly projecting end 16. To accommodate the angularly disposed rod 12 it is obvious that the bracket 15 must be longer than the bracket 16 and the distance or variation and the proportionate length of these ends 15 and 16 would be governed by the angle of the rod 12 so as to keep the mail box 10 suspended in a horizontal position on the rod 11.

The bracket 14 is shown fastened by means of bolts 17 to a conventional type of post shown as 18 and the lower end of the angularly disposed rod 12 is shown supplied with washers 19 to keep the rod 12 in a fixed relative position as to height.

The mail box 10 is shown mounted onto cross members 20 illustrated in Figure 2 and these cross members also act as supports for outwardly extending guard members shown as 21 for the protection of the mail box 10 when an impact is placed thereon. The cross members 20 are shown attached to the rod 11 by means of clamp members 22 in the form of metal straps or the like and I show pins 23 disposed through the clamp members 22 into the rod 11 to keep the entire mail box assembly and guard members in a fixed position and from turning. The guards 21 are attached to the cross members 20 as shown at 24. The upper end 15 of the bracket 14 is provided with aperture 25 and a lower end 16 of the bracket 14 is provided with an aperture 26 through which the angularly disposed rod 12 is placed and which apertures act as a journal or a bearing for the rod 12.

There is a spring leaf 27 attached to the bracket 14 at 28, this spring leaf 27 has a radial contour and projects outward from the point 28 and is equipped with a block 29 which may be welded onto the dependent end of the spring 27. The block 29 has a radial extending portion 30 which is arranged to engage a recessed portion within a recessed block 31 attached to the angularly disposed rod 12 and a pressure adjusting block 32 is shown wedged between the spring leaf 27 and the face of the bracket 14. This pressure ad-

55

justing block 32 may be fastened to the face of the bracket 14 or may be held in position between the bracket 14 and the spring 27 by frictional contact. Obviously, when the block 32 is forced downward, it will cause a greater amount of pressure of the block 29 into the recessed block 31 and the function of the blocks 29 and 31 is to retain the arm 11 and 12 in a fixed position and due to the resiliency of the spring 27 it will be caused to disengage when the arms 11 and 12 are radially moved due to an impact onto the guard member 21 adjacent to the mail box 10.

In the chosen embodiments of my invention there are features not heretofore disclosed in the prior art and although I have shown a particular arrangement of the component parts constituting the device I am fully cognizant of the fact, that many changes may be made in their form and configuration without effecting their operativeness or without effecting the spirit of my invention or the scope of the appended claims.

Having thus described my invention what I claim and desire to secure by Letters Patent in the United States is:

1. A device of the character described to be used in combination with a mail box, said device comprising a horizontal rod having a downwardly extending angularly disposed portion, a support bracket adapted to receive the angularly disposed portion of said rod, a resilient member attached at one of its ends to said support bracket, said resilient member provided with a convexed contact, said downwardly disposed portion of said horizontal rod equipped with a concave member, said concave and convexed members placed in direct alignment with one another for maintaining said rod in a normal outwardly projecting position and arranged to automatically return said rod is temporarily swung in either direction, and

means for attaching said support bracket to a stationary object.

2. A device of the character described to be used in combination with a mail box, said device comprising a horizontal rod having one of its ends extending downward in angular relation to said horizontal portion, a support bracket, said bracket equipped with an upper and lower portion extending outward therefrom, the upper portion being longer than the lower portion, said upper and lower portions of said support bracket provided with apertures acting as bearings for the downwardly extending portion of said rod, a resilient member attached at one of its ends to said support bracket, said resilient member provided with a convex contact member, said downwardly disposed portion of said horizontal rod equipped with a concave contact member, said concave and convex members placed in direct alignment with one another for maintaining said rod in a normal outwardly projecting position and arranged to automatically return said rod to said normal position when said rod is temporarily swung in either direction, means for attaching said support bracket to a stationary object, and means for attaching said mail box toward the outwardly extending portion of said horizontal rod.
